UNITED STATES PATENT OFFICE.

AUGUST R. SCHOENKY, OF SOMERVILLE, MASSACHUSETTS, ASSIGNOR TO REECE SHOE MACHINERY COMPANY, OF BOSTON, MASSACHUSETTS, A CORPORATION OF MAINE.

SEWING MACHINE.

Application filed July 28, 1919. Serial No. 313,732.

To all whom it may concern:

Be it known that I, AUGUST R. SCHOENKY, a citizen of the United States, residing at Somerville, in the county of Middlesex and State of Massachusetts, have invented a new and useful Sewing Machine, of which the following is a specification, reference being had therein to the accompanying drawing.

This invention is a novel sewing machine, 10 more especially a shoe sewing machine of the class known as a welt-and-turn machine, in which the shoe insole is stitched to the shoe upper and, preferably, also to the welt strip. The principal object of the present 15 invention is to improve the operation of such a machine and more especially as to the manner and means of feeding, guiding and applying the welt to be stitched to the shoe. Other objects and advantages of the present 20 machine will be explained hereinafter or will be apparent to those skilled in the art. To the attainment of such objects and advantages the present invention consists in the novel machine, mechanisms, combinations, 25 arrangements and devices shown, described and claimed.

In the accompanying drawings forming a part hereof, Figure 1 is a left elevation of the pertinent parts of a shoe welt stitching machine embodying the present invention.

Figure 2 is a diagram showing the relation of the shoe, the welt strip and the welt guide, which is also a welt feeding means 35 but is for convenience termed a welt guide.

Figure 3, in left elevation, shows a detail of the looper which places the thread on the hooked needle.

Figure 4 is a right elevation of the parts 40 seen in Fig. 1, or rather those which appear from the opposite side of the frame wall.

Figure 5 is a left elevation on an enlarged scale, of certain parts seen in Fig. 1.

Figure 6 is a section taken on the plane 45 6-6 of Fig. 5.

Figure 7 is a similar section taken on the plane 7-7 of Fig. 5.

Figure 8 is a section taken on the plane 8-8 of Fig. 5.

50 Prior welt stitching machines are shown in Zaleski and Schoenky Patent No. 1,288,366, patented December 17, 1908, and Patent No. 1,361,952, patented December 14, 1920, which may be referred to for many general 55 features and matters of construction and de-

tail not forming part of the present invention nor illustrated herein.

As in the prior machines referred to, the present machine may comprise the usual stitching instruments including the work 60 rest or bumper A against which the shoe is held during stitching, the channel guide B which engages the preformed channel in the insole, the oscillating, curved, hooked needle C, the thread looper D, the thread hook or 65 finger E, the feed device G, and the welt guide or feed device H. The member H may also be termed a back gage as it is used in making turn shoes in which there is no welt. It is mounted at the forward end of 70 a sliding shank h to be hereinafter referred to, and the other instruments are suitably mounted for their proper movements and actuated in harmony.

The most of the parts herein shown are 75 mounted on a frame part or upright wall 10. This is the left hand one of the two spaced apart walls shown in the prior machines. The parts to the left of the wall, 80 namely, the parts seen in Fig. 1, may be termed outside parts for convenience, and similarly those to the right of the wall or between the walls, shown in Fig. 4, may be called inside parts. The main or operating shaft 11 utilizes the frame wall 10 as one 85 of its bearings. This may be provided with cranks rather than cams for operating the greater part of the stitching instruments, as in said prior machine. Thus, an outside or left hand crank 12 is shown which actuates 90 the connections shown in Fig. 4. The usual hand wheel 14 may be provided at one end of the shaft.

The crank driven connections for operating the sewing instruments may be of various forms and arrangement. For example, the inside crank 13 is shown as provided with a pitman 15. As the crank rotates, the pitman is controlled in its movements by swinging arm 16 pivoted forward of the shaft. The extremity of the pitman is connected by a link 17 to the big lever 18 fulcrumed at its rear end, and at its front end connected by curved link 19 with the needle block carrying the needle C. Thus, the needle is caused to oscillate, and when moving forwardly it passes through the welt, upper and insole lip, where it receives thread from the looper D and retracts to form the 100 stitches in the usual manner.

The looper may be operated as follows. The outside crank is provided with a pitman 21 connecting with a lever 22 centrally pivoted and having at its far or front extremity a link 23 forming a connection to an oscillating toothed segment 24 meshing with a pinion 25 on a short horizontal shaft, the right end of which has a bevel gear meshing with a bevel gear 27 at the top end of the 5 looper D. The looper rotates on its longitudinal axis for something over one revolution and then reverses. It thus applies a 10 loop to the hook of the needle on each forward stroke of the latter. It will be understood that the thread from the supply passes 15 down through the hollow interior of the looper. I have shown extending through the looper an inclined thread tube 30, see Figs. 3 and 4. The lower end or exit of this tube 20 is the part that applies this loop to the needle. I believe it new to afford a relative adjustment. This I herein secure by rendering the thread tube 30 longitudinally, 25 adjustably shiftable. The upper portion 31 of the tube is threaded and provided with a hexagonal head 32. By this means, the head may be turned and causes the tube to ascend or descend for such adjustment as desired. A lock nut 33 secures adjustment. 30 The thread finger E co-operates with the looper by holding the thread which the looper applies to the needle. The finger may be actuated by means of a link 35 extending from the lever 22, before mentioned, 35 to an arm 36 mounted on a short horizontal shaft 37 to which the finger E is secured. Thus, the finger is vibrated in each cycle. 40 The shoe rest or bumper A has a shank a which is guided at the inside of the frame wall, as shown in Fig. 4, by means of guides 39 and 40. A spring 41 tends to pull the bumper forward but permits it to yield at certain times, for example, during the feeding of the work, to adapt itself to the 45 position of the work. To lock forward the bumper at certain times, for example, during the retraction of the needle, the following may be employed. I show a depending arm 43 which swings with the before-mentioned 50 lever 18. A link 44 extends downward from the arm to a bell crank lever 45. This has a laterally extending pin 46 adapted to engage and actuate a sliding pin 47 which, when thrust forwardly, unlocks and releases 55 the bumper. When the needle is in the work and the pins 46 and 47 stand rearwardly, the bumper is locked against rearward yielding by means of a ball or rolling element 48 normally pressed rearwardly by a spring- 60 pressed rod 49 so as to engage and wedge between the upper surface of the bumper and the inclined surface of a cam or wedge 50. The bumper is held by the wedging of the ball except when the releasing pins 65 thrust the ball forward, as described. The

rolling element 48 is preferably a hardened sphere, of the type used in ball bearings.

Coming now to the welt guide H, mounted on its sliding shank h, the latter slides forwardly and rearwardly in a slideway or 70 recess cut into the inner side of the frame wall 10, as seen in Figs. 4 and 6. The plate 39 which confines or guides the bumper A is extended upwardly and serves also to confine the welt guide shank near its front end, while its rear end is confined by plate 54.

The shank h is constantly pulled forward by a spring 55. This being yielding, permits the welt guide to adapt itself to the 80 position of the shoe when inserting the work and at a certain time during each stitch cycle. To limit the forward movement and take impact, a rubber pad 56 is provided behind the retaining plate 54. A 85 bolt 57 is threaded in a boss 58 on the shank h and this, when it comes forward, strikes the rubber pad. It is adjustable, and the lock nut 59 fixes the adjustment so as to determine the maximum forward position 90 of the welt guide.

Referring to the diagram, Figure 2, it will be understood that as the shoe is fed it is guided from the channel x in the insole. The last or upper y extends outwardly beyond the insole to varying extents. The welt strip w passes from the supply through the welt guide H and thence to the point where the needle C applies the stitches through the welt, the upper and the insole lip. It is customary to feed or draw welt from the supply while the work is stationary and the stitch is being formed, so that the subsequent feed or advance of the work will find the proper amount of welt ready to be applied. This has customarily been done by retracting the welt guide rearwardly to a predetermined position. During this movement the welt runs through the guide. Subsequently when the guide comes forward to the work it furnishes slack welt, which is taken up by the feed of the work, and it lays the welt against the shoe in a proper position to receive the stitch. 100

This plan is defective, and an object of the present invention is to overcome the defect. As before stated, the last or upper extends beyond the insole in varying amounts as the diagram shows. The welt guide H, when it comes forward, contacts and rests against the upper or last. They form its stop. It will be clear that when the upper projects far beyond the insole, the retracting movement of the welt guide will be less than when the upper extends only slightly. In other words, the action of the welt guide and the resulting feed of the welt are variable. They should be constant, for during the production of uniform stitches the welt feed should be uniform stitch after stitch. 110 115 120 125 130

The present invention accomplishes this purpose by providing a welt guide which retracts, in every stroke, a fixed predetermined amount or distance. It retracts not to a fixed point but to a variable point, and to a fixed distance rearward of its variable forward position determined by the extension of the shoe upper.

Various mechanisms might be used to carry out this invention, but I prefer to employ a retracting member or carriage which in each cycle retracts a fixed amount, and which, prior to each retraction, engages or grips the shank of the welt guide so that, wherever the latter may happen to stand, it will in each cycle be drawn backwardly the same distance, thus drawing off and feeding the same amount of welt strip for each stitch.

For a welt guide retracting means, I have provided a sliding carriage or retractor 60 which slides forwardly and rearwardly at the same incline as the welt guide shank, within a recess or opening 73 cut clear through the frame wall 10. Figs. 1 and 4 show the carriage in place, and Figs. 5 to 8 show the details. The carriage is preferably built-up, and has an upper side block 62 and a lower side block 63 rigidly attached to the body portion of the carriage. The carriage 60 is retained in the wall recess by retaining plates 70, 70 at the left and 71, 71 at the right side of the wall. As seen in Figs. 1, 4 and 5, the shank *h* passes directly through a groove or slideway 61 cut in the carriage. At times the shank slides loosely so that its spring 55 may pull it forward to the work, and at other times is locked so as to retract with the carriage, and at still other times is locked against rearward movement, for example, to hold the guide firmly up to the work during the retraction of the needle.

I will first describe the connections for reciprocating the welt guide retractor or carriage 60, and afterwards the different locking and unlocking means by which the welt guide is rendered free, or is held forwardly, or is drawn rearwardly, in the manner mentioned.

It has already been described how the outside crank 12 through the outside pitman 21 swings the arm 22, which arm controls the pitman movements. A link 64 extends from the pitman extremity to a rocking lever 65 fulcrumed at the rear at 66. A downward link 67 connects the lever with a guiding link 68, and a third link 69 extends from their pivot directly to the carriage 60. As the crank travels round and round, the rock lever swings upwardly and downwardly. It is almost at the top of its stroke in Fig. 1. When it swings downwardly it straightens out the links 68, 69 and throws the carriage forward, to be later drawn rearward on the lifting of the rock lever. It is unnecessary to describe in de-

tail the exact timing and the successive positions of these parts. However, it may be mentioned that links 68, 69 will straighten out and pass slightly therebeyond. Due to this and other factors, the carriage 60 pauses for a substantial fraction of a cycle when in its most forward position. It recedes subsequently at the time that the welt guide should recede in the cycle of operations. The plan of the present invention is to utilize the substantially stationary forward position of the carriage for locking the welt guide forward, and subsequently to utilize the retraction of the carriage to pull the guide rearwardly.

To lock forwardly the welt guide shank *h* in the carriage 60, I have shown a locking device including a ball 75, see Figs. 5, 7 and 8. This is longitudinally movable in a recess in the carriage just above the shank *h*. The carriage or rather the upper side block 62 is formed with a cam or wedge surface 76, and the ball is adapted to wedge between this and the upper side of the shank to lock the latter against rearward movement. A spring-pressed rod 77 tends to hold the ball in locking or operative position. When so held the shank may freely ride forward but would be wedged and held against the slightest rearward sliding. At certain times the shank must be released for sliding rearward, and this may be effected by an unlocking rod 78. This small rod slides in the block 62 and is adapted to push forwardly the ball 75, out of locking position. The rod has an off-set or pin 79 connecting it with a slide 80 fitted at the left face of the carriage and through which the locking and unlocking are controlled. Sliding the slide 80 forward will correspondingly move the rod and displace the locking ball, while moving it rearward causes the ball to be restored to operative position. To actuate the locking and unlocking slide 80, I utilize the link 69, before mentioned. This, during the movement of the carriage, has a rocking action on its pivot. I provide an upward extension 81 from the link, as seen in Figs. 1 and 8. This rocking extension will move forwardly and rearwardly on the carriage, and is arranged to strike in its forward movements a pin 82 on the slide 80, while on its rearward movements its beveled or wedge surface 83 engages a corresponding wedge surface 84 under the head 85 of a pin 86 movable in the slide 80. The pointed end 87 of the pin 86 engages a recess 88 in the rod 78. A spring device 89 holds the pin 86 in the position shown. The operation of these parts is substantially as follows. When the parts are moved to the position shown in Fig. 1, with the carriage rearward and the rocking extension 81 forward, this has moved forward the slide 80 and with it the rod 78, thus displacing the ball 75 and leaving the welt

guide free to adjust itself to the work. At a later point, when the carriage is forward the extension 81 will have swung relatively rearward on the carriage, thus extracting 5 the pin 86 and thrusting relatively rearward the slide 80 and rod 78, permitting the ball 75 to assume locking position beneath the wedge surface 76. At this time the welt guide is locked firmly forward to the work. 10 In the position shown, the machine is ready to receive new work. The operator places the shoe in position. The bumper A and the welt guide H may both be forced yieldingly back as the work is placed. After 15 the machine is started, the described connections permit the locking ball 75 to lock the welt guide forward, as described. During this period the needle retracts. Before the subsequent displacement of the ball to 20 unlock the welt guide, the second set of locking devices, namely at the lower side of the carriage, are rendered effective to lock the welt guide shank to the carriage so that it is compelled to move rearwardly with the 25 next rearward stroke of the carriage. After such rearward stroke is commenced, the upper locking device is unlocked but not until the needle has been completely withdrawn from the work. Subsequently, after the carriage and welt guide have retracted a pre-determined distance necessary for exactly uniform feeding of the welt, the lower locking device opens and releases the shank, which thereupon moves forwardly to the 30 work under the influence of its spring 55. This forward welt guide movement lays the fed strip against the shoe. The feed of the work will then have taken place. The parts are now in position for the next advancing 35 stroke of the needle, which penetrates the welt, upper and lip. Before the needle commences its retraction, tending to displace the work, the bumper and welt guide are again locked forwardly to firmly hold the work 40 in place. This completes the cycle so far as concerns the present invention.

The lower shank locking devices or those by which the retractor or carriage grips and draws rearwardly the shank and welt guide 50 may be as follows. A locking ball 95 is shown lying above a wedge surface 96 on the carriage lower side block 63. It is between this inclined surface and the shank h. A spring-pressed rod 97 tends to wedge the 55 ball into contact with the wedge and shank. This would prevent forward movement of the shank and thereby enable the carriage to pull it rearward. The unlocking rod 98 is adapted to displace the ball. The rod is 60 operated by a pin 99 on a slide 100 mounted at the face of the carriage. A pin 101 outstanding from the slide is engaged by the downward arm 102 of a bell crank lever the forward arm of which is provided with 65 a stud or roller adapted to pass along the

groove or cam slot in a plate 105 fixed to the machine frame. This cam plate is slidably adjustable to vary the timing or extent of welt guide retraction. Thus the upper side of the plate engages a guide 106, and the lower side is guided by a threaded bolt 107 passing loosely through a lug 108 on the frame and held against sliding therein by a cap piece 109. When the bolt is turned, the cam plate is set toward or from 70 the carriage.

The cam plate has an incline followed by a dwell. The incline serves to throw the bell crank lever 102-103 when the carriage is moved forwardly or rearwardly. As the carriage moves rearwardly the cam stud 104 is thrown down in the cam groove. This swings the bell crank and throws the slide 100 relatively to the left, thereby displacing the ball and unlocking the shank h. This terminates its rearward movement and the drawing off of welt strip. When the carriage moves forwardly, the stud 104 swings up through the inclined cam slot into the dwell and forward to its normal position. 80 This movement is without effect, as the gripping or locking effect of the ball 95 is only in the one direction. Obviously, every time the carriage retracts, this being for a pre-determined distance, as explained, the welt 85 guide shank is at once gripped and drawn rearwardly until the unlocking point is reached, always at the same point in the stroke of the carriage, and thereby giving always to the welt guide the same extent or amount of retraction, irrespective of variations in its initial or forward position. 90

In a sense it will be observed that the moving carriage 60 is an actuator for causing welt guide movements. The sliding carriage 105 is only one form which such actuator might take. It might be a rotary or otherwise movable device, but it is preferably movable in a regular manner. This moving actuator goes through its movements regularly, and it stands ready to do its work of retracting the welt guide by a fixed, uniform, or pre-determined amount or distance. The ball 95, and accompanying parts, is in effect a gripper or coupler for coupling the welt 110 guide or its shank to the regularly moving actuator or carriage. When the time comes for the welt guide to retract and measure off welt strip, the shank, being coupled to the actuator, moves with it and is thus drawn rearwardly. Its uniform withdrawal is determined in a suitable manner, either by the extent of movement of the actuator, if it be vibratable, or by the period during 115 which the shank is coupled thereto, if rotary.

It will thus be seen that I have described a sewing machine of the class mentioned, embodying the principles and attaining the objects and advantages of the present inven- 120 125

tion. Since many matters of combination, arrangement, design, construction, and detail, may be variously modified without departing from the novel principles involved, 5 no limitation to such matters is intended except so far as set forth in the appended claims.

What is claimed is:

1. In a welt and turn or analogous sewing machine the combination with the hooked needle, looper and cooperating instruments, of a yielding work rest, a clutch for locking the same forward to the work, a needle actuating lever 18, means for vibrating said lever, and connections 44, 45 from said lever for opening said clutch. 10

2. Sewing machine as in claim 1 and wherein the lever vibrating means comprises a rotating crank 13, pitman 15 thereon and link 17. 20

3. In a welt and turn or analogous sewing machine the combination with the hooked needle, looper and cooperating instruments, of an upright frame wall having an opening therethrough, a back gage having its shank slidably mounted on one side of said wall and extending across said opening, an operating crank shaft passing through said wall, a crank on said shaft at each side of said wall, connections from the crank at the back gage shank side of the wall for actuating the needle, and connections from the other crank for actuating or controlling the shank. 30

4. In a welt and turn or analogous sewing machine the combination with the hooked needle, looper and cooperating instruments, of an upright side frame wall 10, a crank shaft having a crank at one side and another crank at the other side of the wall, a work rest with sliding shank *a* and back gage with sliding shank *b*, both at the same side of the wall, and connections from said respective cranks for controlling said respective shanks. 45

5. Sewing machine as in claim 4 and wherein the two shanks are mounted at the inside of the wall, the work rest shank having a clutch, connections from the inside crank for controlling the clutch, the back gage shank having a clutch, and connections from the outside crank for controlling the back gage clutch and for bodily retracting the back shank. 50

6. In a welt and turn or analogous sewing machine the combination with the hooked needle, looper and cooperating instruments, of a back gage *H*, having shank *h*, a retractor for said shank, adapted to engage and retract it at certain times, and means for reciprocating the retractor, comprising an operating crank 12, pitman 21 thereon, a connection from said pitman to a rear-pivoted lever 65, and a connection from said lever to the retractor. 55

7. Sewing machine as in claim 6 and wherein the connections from lever 65 to the retractor comprise toggle links arranged to give the retractor a pause in its forward position. 60

8. In a welt and turn or analogous sewing machine the combination with the hooked needle, looper and cooperating instruments, of a back gage *H*, having shank *h*, a retractor for said shank, adapted to engage and retract it at certain times, and means for reciprocating the retractor, comprising toggle links 68, 69, and connections for actuating the same to give the retractor a substantial pause in forward position. 70

9. Sewing machine as in claim 8 and wherein the retractor is a sliding carriage bearing a clutch engageable with the back gage shank. 75

10. In a welt and turn or analogous sewing machine the combination with the hooked needle, looper and cooperating instruments, of a back gage *H*, its shank *h*, a retractor carriage, said shank and carriage slideable along the same line, a clutch between said carriage and shank whereby the retraction of the carriage retracts the shank, and means for reciprocating said carriage in a manner to give a substantial pause in forward position, comprising toggle links 68, 69, and connections for aligning the links to move the carriage forward and for moving them slightly beyond alignment to give a pause. 80

11. Sewing machine as in claim 10 and 100 wherein is an operating crank 12 having connections for effecting said movements of the carriage forward to and beyond alignment.

In testimony whereof, I have affixed my 105 signature hereto.

AUGUST R. SCHOPENKY.
